[57] CLAIM

The ornamental design for a video terminal, or similar article, substantially as shown and described.

DESCRIPTION

FIG. 1 is a front elevational view of a video terminal or similar article showing my new design;

FIG. 2 is a right side elevational view thereof, the left side being a mirror image of the right side;

FIG. 3 is a rear elevational view thereof;

FIG. 4 is a top plan view thereof;

FIG. 5 is a bottom plan view thereof;

FIG. 6 is a right side elevational view of the video terminal depicted in FIGS. 1-5, but with its screen tilted more rearwardly relative to its base;

FIG. 7 is a three-quarter isometric view of the video terminal depicted in FIGS. 1-5, showing its front, left and bottom surfaces; and

FIG. 8 is a three-quarter isometric view of the video terminal of FIGS. 1-5 showing its rear, right and top surfaces.
